UNITED STATES PATENT OFFICE.

JOHN S. RAYNOR, OF PHILADELPHIA, PENNSYLVANIA.

CLIP FOR FASTENING METAL LATHS.

Application filed March 17, 1925. Serial No. 16,098.

My invention relates to new and useful improvements in a clip for fastening metal laths, such as expanded or woven wire laths, to plasterer's steel furring irons or bars, and has for its primary object to provide a device of this character which is particularly adapted for use in connection with furring irons or bars having arcuate circumferences such as bars of circular cross section, although they can be used with furring irons or bars of other shapes.

Another object of the invention is to provide a simple and inexpensive device of this character having a high degree of efficiency by holding the laths snug against the furring bars throughout their lengths.

A further object of this invention is to provide a clip which when in use will lock the preceding one and be locked by the succeeding one so that by fastening the last clip of a series all of the clips of said series will be held in position.

A still further object of my invention is to improve the construction of a similar clip shown and described in my application bearing Serial Number 711,521, Filed May 7th, 1924.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1 is a perspective view of a portion of a steel furring iron or bar and a wire lath attached thereto by clips embodying my invention, a portion of the bar being broken away to clearly illustrate the coaction of two clips.

Fig. 2 is a perspective view of one of the clips having a shape particularly adapted for use with bars of rectangular cross section.

Fig. 3 is a similar view of a clip designed for use with bars having an arcuate circumference.

Fig. 4 likewise is a similar view of a modification.

Fig. 5 is a perspective view of a portion of a furring bar and a metal lath fastened thereon by a differently shaped clip.

Fig. 6 is a perspective view of one of the clips shown in Fig. 5.

Fig. 7 is an end view thereof.

In carrying out the invention, 2 represents a furring iron or bar which is generally used in present day building construction to support metal laths or lathing 3 and the plaster carried thereby, it being understood that the metal lath is of expanded or woven formation.

To securely fasten the metal lath to the furring iron or bar, I provide a clip constructed of round, square or flat sections of metal rod or wire fashioned to produce a body 4 with a leg 5 projecting from one end thereof at substantially right angles thereto while from this leg projects a horizontal intermediate section 6 and from the latter projects a downturned portion 7 parallel to the leg 5, said section terminating in an in-turned toe 8 parallel with the body 4 and the parts designated by the numerals 5 to 8 inclusive together form a locking element 80 the use of which will be presently described. At the opposite end of the body is formed a leg 9 also substantially at right angles to said body and from this leg projects a horizontal section 10 substantially at right angles to the leg 9 and said parts 9 and 10 together constitute a stay element.

The above description relates particularly to the clip shown in Fig. 2, but by making the part 6' between the leg 5 and the downturned portion 7 as shown in Figs. 1, 3 and 4, a locking element is provided which is particularly adapted for use in connection with furring irons or bars of arcuate formation while in other respects the clips shown in Figs. 1 and 3 are identical with the one shown in Fig. 2.

Under some conditions it is advisable or preferable to eliminate the in-turned toe from the locking element and this formation is shown in Fig. 4, but otherwise corresponds to the construction shown in Fig. 3.

In practice the metal lath 3 is temporarily secured against the furring iron or bar 2 and

then permanently fastened by means of a series of the clips which are attached one at a time and to place said clips in position one of them is first manipulated so that the locking element is inserted through an opening in the lath on one side of the furring bar and then turned so that the portion 6 or 6' lies across the furring bar with the toe 8 projecting through an opening in the lath on the opposite side of the furring bar as plainly shown in Fig. 1, at which time the body of the clip may be brought into proximity to the lath and the stay element at the opposite end of the clip inserted through an opening in the lath and moved across until the portion 10 lies across and engages the surface of the bar opposite that against which the lath rests. The succeeding clip is similarly connected to the parts with the locking element inside of the stay element of the preceding clip so that the body of the succeeding clip coacts with the leg 9 of the preceding clip to hold or lock it in place and prevent displacement thereof. A series of these clips are placed in position in this manner until the lath is held firmly against the furring bar and the last one of the clips, or more particularly the stay end of said last named clip, is secured in place by a suitable tie 11, such as a piece of wire looped about the body of the clip and the furring bar.

From the foregoing description it will be seen that the toe 8 after passing through an opening in the lath engages the face of said lath and therefore prevents the clip from rotating and although this is quite an advantage it is not absolutely necessary under some conditions and therefore may be eliminated as shown in that form of the device in Fig. 4 and although the clips may rotate they will be locked together and cannot become displaced.

In that form of the invention shown in Figs. 5 and 6, the clips each comprise a body 12 having a leg 13 projecting from one end thereof at right angles thereto and from this leg extends an intermediate portion 14 from which projects the downturned section 15 having a rearwardly or outwardly projecting toe 16 which, as shown in Fig. 7 is in a different plane to that of the body but in endwise alignment with an imaginary line parallel to said body. From the other end of the body 12 projects a leg 17 at substantially right angles to said body and from this leg projects a horizontal section 18 substantially at right angles to the leg. The parts designated by the numerals 13 to 16 inclusive constitute a locking element while the parts 17 and 18 constitute a stay element and the latter is similar to the stay element in the other forms of the device.

In this form of the invention one of the clips is attached to a furring bar by manip-

ulating the clip so as to worm the locking element through an opening in the lock and the body then drawn down toward said lath so that the leg 13 is on one side of the furring bar and the downturned portion on the other side of said bar with the toe 16 lying against the inner surface of the lath, or in other words, this toe does not pass back through the lath as in the other form. The stay end of the clip is then drawn over until it takes a position on the side of the furring bar opposite to that of the leg 13 so that said body assumes a position diagonal to the axis of the furring bar and the stay end is then inserted through an opening in the lath and moved over until the horizontal portion 18 engages that side of the furring bar opposite the lath.

The locking end of the succeeding clip is then inserted through an opening through the lath beyond the stay end of the preceding clip and when properly positioned as above described the toe of the locking element of said succeeding clip will engage the leg at the stay end of the preceding clip and thereby lock it against displacement and rotation.

Of course I do not wish to be limited to the exact details of construction as herein shown as these may be varied within the limits of the appended claims without departing from the spirit of my invention.

Having thus fully described my invention, what I claim as new and useful is:

1. In combination with a furring bar and metal lathing, a series of clips, each of said clips comprising a body portion coacting with the lathing; a locking leg comprising a bar, a toe projecting from the locking leg and contacting with the lathing to prevent rotation of the clip; and a stay leg engaging the same furring bar as the locking leg to hold the body of the clip snugly against the lathing, the locking legs of each succeeding clip engaging the body of the preceding one to hold the stay leg of said preceding clip in place against the furring bar.

2. As a new article of manufacture, a clip fashioned from a section of wire like metal to provide a body, a leg projecting at one end at substantially right angles thereto, an intermediate portion projecting from said leg, a downturned section extending from said intermediate portion, an inturned toe projecting from the downturned section, a leg projecting from the opposite end of the body at substantially right angles thereto, and a section projecting from said leg at substantially right angles to the latter.

3. A clip for securing metal laths to furring bars consisting of a section of suitable metal so fashioned as to form a body, a stay element at one end of the body for engagement with the furring bar, and a locking element at the opposite end of the body for

embracing the furring bar, said locking element including a toe for cooperation with a lath to prevent rotation of the clip.

4. A clip for securing metal laths to furring bars consisting of a section of suitable metal so fashioned as to form a body, a stay element at one end of the body for engagement with the furring bar, and a locking element at the opposite end of the body for

embracing the furring bar and coacting with the stay element or adjacent clip to hold said adjacent clip in place, said locking element including a toe for coaction with the lath to prevent rotation of the clip.

In testimony whereof, I have hereunto affixed my signature.

JOHN S. RAYNOR.
